UNITED STATES PATENT OFFICE.

THOMAS J. COO, OF TORONTO, ONTARIO, CANADA, ASSIGNOR TO UNDERWOOD TYPE-WRITER COMPANY, OF NEW YORK, N. Y., A CORPORATION OF DELAWARE.

TYPE-WRITING MACHINE.

1,194,361.

Specification of Letters Patent. Patented Aug. 15, 1916.

Application filed July 3, 1914. Serial No. 848,742.

To all whom it may concern:

Be it known that I, THOMAS J. COO, a subject of the King of Great Britain, residing in the city of Toronto, Province of Ontario, Dominion of Canada, have invented certain new and useful Improvements in Type-Writing Machines, of which the following is a specification.

This invention relates to work-feeding means for the revoluble platens of typewriting machines, and particularly to means for conveniently introducing and line-feeding a stiff card, especially a stencil address card, which usually comprises a sheet of thin wax-coated paper with a protecting frame of heavy stiff cardboard.

One of the leading features of my invention involves the introduction of the card bottom edge downward at the front of the platen and moving it downwardly and backwardly around the under side of the platen until the top or leading portion thereof is in position to be written upon.

I am aware that it has heretofore been proposed to introduce sheets of paper downwardly at the front of the platen, but the present devices provide for the control of stencil cards and other stiff work-pieces.

The present construction primarily comprehends the employment of hard biting or work-indenting rolls, which run upon the front side of the platen to grip or indent the side edges of the card, these rolls being made of steel or other metal and having their surfaces knurled or consisting of a series of points or edges. These rolls are pressed very forcibly against the front of the platen, and in practice, by reason of their indenting or biting action, are found to grip and feed along the bottom edge of the card, even when the same is of substantial thickness, and to be effective in feeding the card downwardly and forcing it to find its way down around the front of the platen and under the same; the card being guided under the platen by a suitable apron or deflector. From said biting rolls there leads downwardly a pair of guide fingers or clips, which at their lower portions are mounted upon suitable devices arranged upon the platen frame, these fingers or clips serving to deflect and guide the lower edge of the card as it descends, and also serving to hold the rolls very firmly against the front of the platen.

The front edges of the bottom apron or deflector, which guides the cards backwardly under the platen, are also rolled over forwardly, to form a chute to receive and control the bottom edge of the card as it descends beyond said rolls. The portion of the card between the guide fingers tends to bulge out, but this tendency is overcome by the fingers constructed as described. The usual feed rolls which run upon the bottom of the platen may also be employed, to aid in feeding the card backwardly during the introduction thereof, and forwardly during the writing thereon; such feed rolls being usually made of soft rubber. The card feeding fingers or clips, with their knurled metal rolls, are preferably mounted detachably upon the machine, and in order not to necessitate extensive changes in the machine itself, I provide spring sockets upon the card fingers, which may catch over the shaft of the usual bottom feed rolls. Above said feed roll shaft I preferably provide retaining pins upon the front portions of the bottom paper guide or apron; these retaining pins serving as fulcrums for the spring fingers. These fulcrum pins may be withdrawn, so as to permit the detachment of the card feeders from the machine, and to permit the machines to be used in the ordinary way for sheets of paper.

Other features and advantages will hereinafter appear.

In the accompanying drawings, Figure 1 is a part-sectional perspective view of that portion of a typewriter carriage including the platen frame, with platen and feed rolls, and also including my improved feed and guide rolls carried by the bottom apron, for use with stiff work-pieces. Fig. 2 is an end elevation of the same, partly in section and with a portion of the platen frame broken away to afford a better exposure of the operative parts. Fig. 3 is a perspective view of the bottom apron, detached from the machine, showing the means thereon for supporting the spring fingers carrying the rolls aforesaid. Fig. 4 is an enlarged detail front vertical section of one of my improved card feeding and guiding rolls, with its supporting spring finger, the latter being partly broken away. Fig. 5 is a perspective detail view of a spring finger carrying a roll. Fig. 6 is a detail view showing a stiff work-piece gripped by the hard biting roll,

being pressed to the platen, and just entering between the rolled edge of the paper apron and the platen.

The present invention having relation to certain means whereby a stiff work-piece, like a stencil card, may, when introduced downwardly over the printing surface upon the platen, be guided around the front and lower portions of the platen surface while being held snugly against the printing portion of the platen surface, I have illustrated herein such portions of an Underwood typewriting machine as correlate with said improvements, including a platen frame 1, a platen 2 supported therein, and a line-space wheel 3 operated by a pawl 4 on a spring returning sliding bar 5; also the platen axle 6, with its finger-piece 7, paper shelf 8, and the usual front and rear feed rolls 9 and 10, and tie-rod 11.

The bottom paper apron 12, which is modified in the present construction, is curved to conform to the curvature of the platen, and has the usual slotted ears 13 by 25 which it straddles and is supported upon the tie-rod 11, being thus in operative position beneath the platen; also said paper apron has notches 14 in its opposite sides, to receive the aforementioned feed rolls.

In order to fulfil the main purpose of my invention, I provide separate spring fingers or clips 15 spaced apart and extending upwardly from the forward edge of said paper apron, said fingers each terminating at its upper end in a roll 16, formed of steel or other hard material with a roughened or suitable gripping surface, said rolls being rotatably supported by said fingers, and as here shown being each carried by a pin 17 that is mounted in a yoke formed by lugs 18, extending from the material of the finger. Each spring finger 15 at an intermediate point therein, is folded or creased to form a spring socket 19, whereby said spring finger 45 may be swung over the rod or shaft 20 which carries the forward feed rolls 10, the location of said rod or shaft 20 being suitable, in the example of typewriting machines with which this invention is illustrated, for the purpose of localizing said spring fingers, so that their rolls may lie in an appropriate position in the performance of their function.

To afford fulerums for the spring fingers or clips, and in order that the rolls they carry may be pressed with the requisite degree of force against the platen, for the purpose stated, a suitable slotted bearing is provided for each finger, in the forward edge of the apron; and in order that said bearings may be capable of opening to allow removal of the spring fingers so that the machine may be used with ordinary work-sheets, I provide at the front side of each bearing slot a sliding pin 21 which en-

gages in lugs 22, upon the paper apron, at opposite sides of the finger, said lugs having orifices to receive said pins, and each pin having a bent-over portion 23 forming a handle by which said pin may be shifted in and out of engagement. Preferably each pin has an enlarged terminal portion 24, which, while capable of sliding within the orifice in the lugs which supports said end, cannot be withdrawn through the orifice in the opposite lug, thereby preventing liability of these pins becoming disengaged and thus being lost. But since the large pointed portion of the pin, when withdrawn as far as it will go, would lie in the path of the spring finger which it retains, the spring finger is narrowed at that point, as at 25, to be rendered capable of being lifted out of its bearing. By the means described, it is a very simple matter to remove the spring fingers, as will be observed, and also to reinsert them upon occasion.

The free ends 26 of the spring fingers 15 extend rearwardly beneath the paper apron 12, and engage with the upper surface of the tie-rod 11, thus forming anchoring arms whereby the tensional hold of said spring fingers upon rod or shaft 20 by their spring sockets 19, is rendered more secure, and an additional tensional bearing is provided whereby the secure support of said spring fingers in their adjusted positions is maintained, the character of the connecting means for said spring fingers throughout allowing the quick and convenient removal or attachment of these devices from and to their operative positions.

On account of the great strength of the spring fingers 15, the rolls 16, which are held against the platen surface by the compression of said spring fingers between said surface and the fulcrum pins 21, are capable of overcoming the resistance presented by a stiff work-piece, such as a stencil card, when interposed between said rolls and the platen, and thus act to hold said work-piece against the platen surface in the neighborhood of the printing line thereon while said work-piece is being flexed so as to conform to the contour of the platen in passing there-around. The spring fingers 15, which extend from the forward edge of the paper apron 12 in their adjusted position, are themselves curved to catch the lower edge of the work-piece in introducing said work-piece downwardly across the front of the platen, said spring fingers guiding the bottom edge of the work-piece to the edge of the said paper apron 12, which edge is rolled or flared outwardly, as at 27, to facilitate entry of the work-piece at its lower edge between said paper apron and the platen, in its continued downward travel, whereby said paper apron is enabled to guide the lower portion of the flexed work-

piece around between it and the bottom of the platen. Also the forward edges of the recessed or notched portions 14 of the paper apron within which the forward feed rolls 5 10 lie, are rolled or flared outwardly, as at 28, for a similar purpose. Thus, any tendency of the stiff work-piece to bulge outwardly at its central portion is met and overcome through the succeeding flared 10 15 20 25 30 35 40 45 50 55 60 65 70 75 80 85 90 95 100 105 110 - rolls with hard, biting surfaces also extending forwardly from said paper apron, in advance of the flared edges thereof, and means for pressing said rolls upon the platen in the neighborhood of the printing zone thereon, to enable said rolls to receive the bottom edge of the stiff work-piece and conduct said work-piece downwardly to the flared edges of said paper apron, for entry between said apron and platen, and said apron conducting the work-piece, in curved or flexed condition, around the bottom of the platen in proximity thereto.
4. In a typewriting machine having a revoluble platen, the combination of a paper apron supported beneath the platen and having forward edges rolled or flared away from the platen to receive a downwardly introduced stiff work-piece, curved spring fingers extending from said apron to guide the work-piece to said apron edges, and feed rolls carried by said spring fingers and having hard, biting surfaces, said rolls pressing upon the platen in the neighborhood of the printing zone thereon, to receive the bottom edge of said work-piece and feed it downwardly to said paper apron.
5. In a typewriting machine having a revoluble platen, the combination of a paper apron at the bottom of said platen, spring fingers extending from the forward edge of said paper apron, hard, biting rolls supported by said fingers, and a releasable bearing upon said paper apron for each finger, said bearings forming fulcrums from which said rolls press against the platen in the neighborhood of the printing zone thereon, to receive and conduct a work-piece downwardly into said paper apron.
6. In a typewriting machine having a revoluble platen, the combination of a paper apron, a spring paper finger fulcrumed thereon, and a feed roll carried by said paper finger and having a hard, biting surface adapted to exert pressure upon the platen in the neighborhood of the printing zone thereon, said paper finger and paper apron being constructed to guide a stiff work-piece between said platen and apron when introduced forwardly to the printing surface in a backward rotation of the platen.
7. In a typewriting machine having a revoluble platen, the combination of a platen frame, a tie-rod therefor, a paper apron, spring fingers fulcrumed on said apron, hard, biting rolls carried by said fingers, and means localizing said fingers to support said rolls in the vicinity of the printing line on the platen, said fingers having each a rear extension to lie upon the tie-rod to assist in holding said spring fingers in their localized position.
8. In a typewriting machine, the combination of a revoluble platen, a platen frame, a tie-rod therefor, a shaft carrying lower forward feed rolls, a paper apron, spring fingers fulcrumed on said apron, and hard, biting rolls carried by said fingers, said spring fingers having a crease or fold to spring over said feed roll shaft to thereby localize said fingers to support said hard, biting rolls in the vicinity of the printing line on the platen, said fingers having each a rear extension to lie upon the tie-rod, to assist in holding said spring fingers in their localized position.
9. In a typewriting machine having a revoluble platen, the combination of a paper apron, spring fingers extending from said apron, hard, biting feed rolls carried by said spring fingers to feed and hold a work-piece to the printing surface of the platen in its introductory and advanced positions, slideable pins releasably engaging said paper apron to form fulcrums for said spring fingers, and means for localizing said spring fingers.
10. In a typewriting machine having a revoluble platen, the combination of a paper apron, spring fingers extending from said apron, hard, biting rolls carried by said spring fingers to feed and hold a work-piece to the printing surface of the platen in its introductory and advanced positions, pins slidable into and out of position upon said paper apron to releasably engage and form fulcrums for said spring fingers, and means preventing complete withdrawal of said pins.
11. In a typewriting machine having a revoluble platen, the combination of a platen frame, a tie-rod therefor, a paper shelf, a paper apron supported on said tie-rod beneath said platen, the rear portion of said paper apron having a bearing against the back surface of said paper shelf, spring fingers fulcrumed on said paper apron, and hard biting rolls carried by said spring fingers and pressing against the platen in the vicinity of the printing line thereof.
12. The combination, with a revoluble platen; of an apron located beneath the platen; and front feeding and guiding devices for stiff work-pieces, comprising a set of spring fingers projecting upwardly from the forward portion of said apron across the front surface of said platen, and a biting roll carried by each finger at its upper end and located substantially opposite the printing zone on the platen, said apron having means for tensioning said fingers, thereby to forcibly press said rolls against said platen, and said fingers and apron being curved to cause the work-pieces to conform to the contour of the platen during their feed movements.
13. In a typewriting machine having a revoluble platen, the combination of a set of spring fingers projecting across the front surface of the platen, biting rolls carried

by said fingers to feed and hold a work-piece to said platen surface; and supporting means for said fingers having slideable pins releasably engaged therewith, to form fulcrums for said fingers.

14. In a typewriting machine having a revoluble platen, the combination of a set of spring fingers projecting across the front surface of the platen; biting rolls carried by said fingers to feed and hold a work-piece to said platen surface; supporting means for said fingers having slideable pins releasably engaged therewith, to form fulcrums for said fingers; and means preventing complete withdrawal of said pins.

15. In a typewriting machine having a revoluble platen, the combination of a set of spring fingers projecting across the front surface of the platen; biting rolls carried by said fingers to feed and hold a work-piece to said platen surface; supporting means for said fingers provided adjacent each finger with a pair of alining, orificed lugs; and a pin slidably mounted in each pair of lugs and forming a fulcrum for the adjacent finger, each pin having means for preventing its complete withdrawal from its respective pair of lugs.

16. In a typewriting machine having a revoluble platen, the combination of a set of spring fingers projecting across the front surface of the platen; biting rolls carried by said fingers to feed and hold a work-piece to said platen surface; supporting means for said fingers provided adjacent each finger with a pair of alining, orificed lugs, the orifice in one lug of each pair being of greater diameter than that of the other lug; and a pin slidably mounted in each pair of lugs, and forming a fulcrum for the adjacent finger, each pin having an enlargement slideable in the larger orifice of the corresponding pair of lugs, but of greater diameter than the smaller orifice of said pair, thereby to prevent complete withdrawal of said pin from said lugs.

17. The combination, with a revoluble platen, and a rod supported below and parallel with the platen axis; of a series of spring fingers pivotally engaged with said rod and projecting upwardly across the front surface of the platen; rolls carried by said fingers at their upper ends and arranged to bear against said platen; a supporting member interposed between the platen surface and said rod and formed with openings through which said fingers extend; and slideable devices releasably engaged with said supporting member and normally bridging said openings to form fulcrums for said fingers.

18. The combination, with a revoluble platen, and a rod supported below and parallel with the platen axis; of a series of spring fingers pivotally engaged with said

rod and projecting upwardly across the front surface of the platen; rolls carried by said fingers at their upper ends and arranged to bear against said platen; a paper apron located beneath said platen and having its forward portion interposed between the platen surface and said rod and formed with transverse slots through which said fingers extend; and slideable pins releasably engaged with said apron and normally bridging the open front ends of said slots to form fulcrums for said fingers.

19. The combination, with a revoluble platen, a frame therefor, and a shaft or rod in said frame; of a series of spring fingers projecting upwardly across the front surface of the platen; biting rolls carried by said fingers and forcibly pressed thereby against said platen surface; and supporting means whereon said fingers are fulcrumed intermediate their ends, each finger having its lower end extended rearwardly to engage said shaft.

20. In a typewriting machine having a revoluble platen, the combination of a set of spring fingers projecting across the front surface of the platen; biting rolls carried by said fingers to feed and hold a work-piece to said platen surface; supporting means for said fingers provided adjacent each finger with a pair of alining bearings; and a pin slidably mounted in each pair of bearings and forming a fulcrum for the adjacent finger, each pin having at one end a crank portion or handle and at the other end an enlargement, thereby to prevent its complete withdrawal in either direction from said bearings.

21. The combination, with a revoluble platen, a frame therefor, and a rod or shaft mounted in said frame; of a set of spring fingers detachably connected with said rod and projecting across the front surface of said platen; rolls carried by said fingers at their free ends and arranged to forcibly bear against said platen surface; and a member mounted in said frame and provided with sliding pins normally engaged with said fingers to form fulcrums therefor, said fingers being cut away at one side to permit their detachment from said rod when disengaged from said pins.

22. The combination, with a revoluble platen, a frame therefor, and a rod or shaft mounted in said frame; of a set of spring fingers detachably connected with said rod and projecting across the front surface of said platen; rolls carried by said fingers at their free ends and arranged to forcibly bear against said platen surface; and a member mounted in said frame and provided with sliding pins movable in one direction to engage said pins and form fulcrums therefor, and having a limited movement in the other direction, said fingers being cut away at one

6
side to clear said pins, when the latter have been moved in said other direction, to permit their detachment from said rod.

23. The combination, with a revoluble platen, a platen frame, and a suitably supported shaft or rod extending along the platen below the printing line; of a clip detachably sprung upon said shaft, and having below said shaft an anchoring arm, said platen frame having a support to be engaged by said anchoring arm, and said clip comprising a yielding member extending upwardly from said shaft around the front of the platen, but clear thereof, past the printing line, and having above the printing line a roll to bear upon the work to hold it in contact with the platen.
24. The combination, with a revoluble platen, and a suitably-supported shaft or rod extending along the platen below the printing line; of front feeding and guiding devices for stiff work-pieces, comprising a set of spring members detachably sprung upon said shaft, and a feed roll carried by
- each spring member at its upper end and 25 having a hard, biting surface, said rolls being forcibly pressed by said spring members against the platen surface substantially at the printing zone.
25. The combination, with a revoluble 30 platen, of front feeding and guiding devices for stiff work-pieces, comprising a set of spring members projecting upwardly across the front surface of the platen from a point below the axis thereof, a feed roll carried 35 by each spring member at its upper end and having a hard, biting surface, said feed rolls being located substantially opposite the printing zone on said platen, and supporting means with which said spring members are 40 detachably connected, constructed to tension the same and thereby to forcibly press said rolls against said platen.
